G. E. McLANE.

COMBINED LEVEL, SQUARE, PLUMB, AND BEVEL.
APPLICATION FILED FEB. 12, 1913.

1,125,861.

Patented Jan. 19, 1915.

UNITED STATES PATENT OFFICE.

GEORGE E. McLANE, OF PHILADELPHIA, PENNSYLVANIA.

COMBINED LEVEL, SQUARE, PLUMB, AND BEVEL.

1,125,861.

Specification of Letters Patent.

Patented Jan. 19, 1915.

Application filed February 12, 1913. Serial No. 743,023.

To all whom it may concern:

Be it known that I, GEORGE E. McLANE, citizen of the United States, residing at Germantown, Philadelphia, in the county of Philadelphia and State of Pennsylvania, have invented certain new and useful Improvements in Combined Levels, Squares, Plumbs, and Bevels, of which the following is a specification.

10 This invention aims to provide a combined bevel, square, plumb and level, and relates more particularly to an attachment for carpenters' squares, the same being adapted for use in ascertaining when work 15 against which the square is applied is level or plumb, or if neither, at what angle it is beveled or inclined.

It is one aim of the invention to provide an attachment for carpenters' squares of 20 the character above mentioned which may be readily applied to the square and may be readily detached therefrom when it is desired to employ the square alone.

The further aim of the invention is to so 25 construct the attachment that when in use in connection with the square, the desired tests as to bevel, plumb and level, may be made by placing one or the other of the arms of the square against either the upper 30 or under side of the work, depending upon which side of the work is the more accessible.

For a full understanding of the invention reference is to be had to the following description and accompanying drawing, in 35 which:

Figure 1 is a side elevation illustrating the instrument embodying the present invention. Fig. 2 is a vertical transverse sectional view illustrating the manner in which 40 the swinging indicator arm of the instrument is hung. Fig. 3 is a vertical sectional view on the line 3—3 of Fig. 2. Fig. 4 is a view similar to Fig. 1 illustrating a slight 45 modification of the invention. Fig. 5 is a view in elevation of the upper end of the modified form of the swinging indicator arm shown in Fig. 4.

Corresponding and like parts are referred 50 to in the following description and indicated in all the views of the accompanying drawing by the same reference characters.

In the drawing, the square in itself is 55 illustrated as including the usual arms 1, 2, which of course, extend at right angles with respect to each other, the square

being of the ordinary form except for certain scales which are marked upon its arms and certain openings which are formed therein to receive the pivot for the swing- 60 ing indicator arm.

In that form of the invention shown in Figs. 1 to 3 inclusive, of the drawings, the square is formed at the juncture of its arms 1 and 2, with an opening 3 which is circular except at two points in its wall, at which points, notches 4 and 5 are formed, the points of location of these notches being co-incident with lines extending midway between the edges of the arms 1 and 2, respectively. The arm 1 of the square is formed with an opening 6 provided in its wall with a notch 7 which is presented toward and in alinement with the notch 4 in the wall of the opening 3. The opening 6 is located at the end of the arm 1 and the arm 2 is formed at its end with an opening 8 the wall of which has a notch 9 presented toward the notch 5 and in alinement therewith. The face of the arm 1 of the square 80 adjacent the notch 4 has marked upon it an arcuate series of scale marks indicated at 10, the purpose of which will be presently explained. Also, for a purpose to be presently explained, the face of the arm 2 is 85 formed with a similar series of scale marks 11 located opposite and adjacent to the notch 5. The arms 1 and 2 are further provided, respectively, with series of scale marks 12 and 13, located near the openings 90 in their ends, and in practice, these scale marks 10, 11, 12 and 13 are respectively equidistantly spaced from the notches 7, 9, 4 and 5. The face of each arm 1 and 2 is furthermore provided with a series of scale 95 marks 14 which indicate the bevel or angle of inclination of a piece of work against which the instrument is disposed, when the swinging indicator arm registers therewith, in the manner to be presently pointed out. 100

In that form of the invention shown in Figs. 1 to 3 inclusive, the swinging indicator arm is indicated by the numeral 15 and is flat-sided and has parallel lateral edges 16 and at one end is tapered to an indicating 105 point 17. At its other end the arm 15 is provided with a pivot stud 18 which projects from one face thereof and is substantially circular in cross section, as shown in Fig. 3 of the drawing. This stud 18 is provided at 110 its end with a head 19 which is of a diameter slightly less than that of either of the open-

ings 3, 6, or 8 and the stud 18 is of such cross-sectional diameter as to be freely received within the notches formed in the walls of any of these openings. At this point it will be apparent that the head 19 is insertible through any one of the openings 3, 6 and 8 so that the stud 18 may engage in any one of the notches 4, 5, 7 and 9, and it will be noted that the indicator arm 15 is of such length that when its stud 18 is engaged in the notch 4 its indicator end will register with the scale 12; and when engaged in the notch 5 the said end will register with the scale 13; when in the notch 9 with the scale 11, and when in the notch 7 with the scale 10.

Before proceeding to a description of the manner of using the instrument that form of the invention shown in Figs. 4 and 5 will be described.

In the form shown in Figs. 4 and 5, the arms of the square are formed adjacent the point of juncture of their longitudinal median lines with slots 20 which correspond in function to the opening 3 and the notches 4 and 5 in the wall thereof; these slots 20 extending longitudinally with relation to the respective arms of the square. The swinging indicator arm of this form of the invention is indicated by the numeral 21 and is formed with a stud 22 substantially of the same cross-sectional contour as the stud 18 and this stud is provided with a head 23 which is of a width and length to permit of its being inserted through the openings 20, the said head extending transversely of the arm 21 so that when the stud 22 is engaged in either end of either of the slots 20 the head 23 will extend transversely of the respective slot and disengagement of the stud will be prevented in the same manner as by the provision of the head 19 in the first described form of the invention.

From the foregoing it will be apparent that the principles of the invention may be embodied, if desired, in a tri-square and that the openings 3, 6 and 8 may be located otherwise than as shown in Fig. 1 of the drawings.

In using the instrument, the head 19 is inserted through one or another of the openings 3, 6 and 8 and one or the other of the arms of the square is then disposed against the work, whereupon the indicator arm 15 will coöperate with one of the scales upon the arms of the square and indicate the plumb, level, inclination or bevel of the work. More specifically, if the instrument is to be employed, for example, in determining whether or not the work is plumb, and the piece of work is so located that the test must be made by disposing the instrument against the left-hand face thereof, the pivot-stud 18 is engaged in the notch 5 and the edge of the arm 2 is then disposed against the face of the work, the indicator end 17 of

the arm 15 coöperating with the scale 13 to indicate whether or not the work is plumb. Under some circumstances it may be found desirable to reverse the square and engage the pivot stud of the indicator arm in the notch 7 so that the indicator end of the arm will coöperate with the scale 10, the edge of the arm 1 being disposed against the left-hand face of the work. In like manner where a test is to be made by disposing the instrument against the right-hand face of the work, the pivot stud is engaged in the notch 9 and the indicator arm coöperates with the scale 11, or the stud may be engaged in the notch 4, whereby the arm will coöperate with the scale 12.

From the foregoing it will be readily understood how the instrument may be employed in ascertaining whether or not a piece of work is level, whether the instrument is to be disposed against the upper or the under side of the work, and it will also be understood that when the pivot stud is engaged in either of the notches 4 and 5 and one arm or the other of the square is disposed against the inclined face of a piece of work, the angle of inclination of the work or the angle of its bevel will be indicated by the intersection of one or the other of the lateral edges 16 of the indicator arm 15 with the inner edges of the arms 1 or 2 of the square at the points indicated by the intersection of the ends of the scale marks 14 with the edges of the arms 1 or 2 as the case may be.

It will be observed that when it is desired to use the square by itself, the indicator arm may be readily and quickly detached and laid aside until again required for use.

Having thus described the invention what is claimed as new is:—

1. In an instrument of the class described, a member having arms relatively angularly positioned, and an indicator arm arranged to be pivotally supported for free swinging movement at the juncture of the arms or at the end of one arm, the arms being provided with indication marks with which the indicator arm is arranged to coöperate when pivotally supported at one or the other of said points.

2. In an instrument of the class described, a member having arms relatively angularly positioned, one of the arms being provided with a transverse series of indication marks and at one edge with a scale, and an indicator arm pivotally supported upon the said member and arranged at its free end to coöperate with the indication marks upon the arm and to coöperate at one edge with that edge of the arm at which the scale is located.

3. In an instrument of the class described, a member having relatively angularly disposed arms and formed at the juncture of

its arms with an opening, the wall of the opening being formed with notches arranged longitudinally of the respective arms, each of the arms having an indication mark spaced from the respective notch, and an indicator having a headed stud engageable through the opening and arranged to seat in either of the notches, the indicator being arranged to coöperate with the indication mark upon one of the arms when the stud is engaged in the notch disposed longitudinally of the respective arm.

4. An instrument of the class described comprising a square provided at its corner and at its ends with openings having notches in their walls, said notches being disposed longitudinally of the respective arms of the square, and the said arms being provided with scales along their edges and

on their sides with transverse scales disposed on arcs respectively concentric with the openings at the ends of the respective arms and the opening at the junction of the arms, and an indicator arm provided at one end with a pivot adapted to engage any one of the openings in the square and having an indicating point at its opposite end adapted to move over the scale concentric with the opening the notch of which is engaged, the edges of said arm coöperating with the scales along the edges of the arms of the square.

In testimony whereof I affix my signature in presence of two witnesses.

GEORGE E. McLANE. [L. S.]
